Primary Examiner — Darlington Ly*(74) Attorney, Agent, or Firm* — Westerman, Hattori, Daniels & Adrian, LLP(57) **CLAIM**

The ornamental design for a front cowl for motorcycle, as shown and described.

DESCRIPTION

FIG. 1 is a perspective view from the front and right side of a front cowl for motorcycle;

FIG. 2 is a perspective view from the front and left side thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a front and right side perspective view thereof, in which the article is shown installed in an environmental motorcycle.

The broken lines showing a motorcycle in FIG. 7 is provided for the purposes of illustrating environmental structure; whereas all other broken lines in the drawings illustrate portions of the front cowl for motorcycle. All subject matters that are shown in broken lines form no part of the claimed design.
